ROBERT HITCHCOCK, OF SPRINGFIELD, MASSACHUSETTS.

Design No. 3,794, dated December 21, 1869.

DESIGN FOR A CAR-VENTILATOR.

The Schedule referred to in these Letters Patent and making part of the same.

I, ROBERT HITCHCOCK, of Springfield, Hampden county, Commonwealth of Massachusetts, have invented and produced a new and original Design for Car-Ventilator Case, of which the following is a specification.

The nature of my design is fully represented in the accompanying drawing, to which reference is made.

I will now describe the form of the case, as shown in the drawing, which shows the outline of the front or back end or section of the ventilator-case.

The case is formed of tin or similar sheet-metal, bent into the shape shown, that is, with the side A in a straight line, nearly or quite horizontal, the side B at right angles to the same, the two being joined by a slight curve at a, for convenience in bending, but this is not an essential part of the design, as the angle may be formed completely, if desired.

Upon the side A, I form a flange, b, for attaching the case to the side of the car.

The top side C is formed straight for a part of the distance across it, as shown, and also has formed the flange b', for the same purpose as the flange b.

This straight part C of the top, and the straight part of the side B, are joined by a curved line, D, as shown.

The advantage of this form of case is, that while neat in shape and appearance, it gives, where it is most needed, a large surface, namely, at the bottom where the opening is presented to the air, while the upper part has, in its contracted form, plenty of room for the devices I use in my ventilator, made under my various patents.

I claim, as my invention—

The design for car-ventilator case, as shown and described.

ROBERT HITCHCOCK.
